UNITED STATES PATENT OFFICE.

GEORGE H. GROSS, OF TOPEKA, KANSAS.

CIGARETTE CONTAINER.

Application filed September 12, 1924. Serial No. 737,408.

This invention relates to containers and more particularly to a container for cigarettes.

Ordinarily, cigarettes are wrapped in a paper wrapping folded and sealed at each end, and in opening the package it becomes necessary to tear open at least one corner of the upper end of the package, in order to gain access to the cigarettes. As the cigarettes are more or less tightly packed within the wrapping, the removal of the first and even the second cigarette is seldom accomplished without mutilating the end of the cigarette which is, of course, a disadvantage. Furthermore, if a package of cigarettes is opened in this manner, the opening remains uncovered and the cigarettes quickly dry and lose their aroma. The present invention, therefore, has as one of its objects, to provide a container for cigarettes which while normally maintaining the closed position so as to prevent loss of the aroma of the tobacco and drying out thereof, may be readily opened without any mutilation of any part 10 of the container and in such manner as to permit of free access to the cigarettes contained therein.

Another object of the invention is to provide a container for cigarettes embodying means whereby the cigarettes will be caused 20 to assume a most accessible position when the container is opened so that no annoyance will be occasioned by the smoker being required to feel about in the container for one or two remaining cigarettes.

In the accompanying drawings:

Figure 1 is a perspective view of the article embodying the invention in the condition in which it will be placed upon the market.

Figure 2 is a perspective view of the article after removal of the outer wrapping thereof.

Figure 3 is a perspective view of the article opened.

Figure 4 is a perspective view of one section of the container.

Figure 5 is a horizontal sectional view taken substantially on the line 5—5 of Figure 3, looking in the direction indicated by the arrows.

Figure 6 is a similar view taken on the line 6—6 of Figure 1, looking in the direction indicated by the arrows.

Figure 7 is a view similar to Figure 5 illustrating a modification of the invention.

As illustrated in the drawings, the container embodying the invention comprises a pair of sections which are substantially of counterpart form and one of which is best 60 illustrated in Figure 4 of the drawings. Each of these sections, which is indicated in general by the numeral 1, comprises a front wall 2, a rear wall 3, a side wall 4, a top 5, and a bottom 6, the side of the section opposite the wall 4 being entirely open. The wall 4 occupies a plane at right angles to the walls 2 and 3, which latter walls are located in parallel planes, the edges of the walls 2 and 3 and the top 5 and bottom 6 70 being located all in a common plane at the open side of the section. The top and bottom walls 5 and 6 are of trapezoidal form and the front wall 2 is, therefore, of less width than the rear wall 3. In assembling 75 the two sections, the open sides of the sections are presented toward each other, adhesive is applied to either the inner surface of the rear wall 3 of the one section or the outer surface of the rear wall 3 of the other 80 section, and the sections at their open sides are fitted one into the other, the adhesive-bearing surfaces being suitably pressed together so as to permanently unite the marginal portions of the wider rear walls 3, as 85 indicated by the numeral 7. In assembling the sections, they are so interfitted that when the container is closed, the free edges of the walls 2 of the sections will substantially meet and register as shown clearly in Figures 2 and 6 of the drawings, the diagonal 90 ends of the top and bottom walls 5 and 6 of the sections overlapping as shown in Figures 2 and 3. The sections of the container may be made of any suitable material such 95 as cardboard, where the container is to constitute an original package, or even heavy paper might serve the purpose, but if the container is to constitute a novelty to be placed upon the market as a cigarette case, the sections may be formed of leather, celluloid, or any other material found suitable for the purpose. In any event, it will be obvious that inasmuch as the united portions of the sections define a thickened back 105 portion, the tendency will be for the sections to remain in closed relation with each other. Likewise, the frictional contact of the surfaces of the top and bottom walls 5 and 6 of the sections, where they mutually overlap, will tend to prevent accidental opening 110 of the container, although it may be readily

opened, as shown in Figures 3 and 5 of the drawings, by swinging the sections 1 backwardly or away from each other about the united portions of their rear walls, thereby exposing the cigarettes contained within the container in such a manner that a cigarette may be conveniently removed without any damage to its wrapper.

- In order that the container may be held closed and suitably protected after it has been packed with cigarettes and while it is on the market, and likewise in order to preserve the aroma of the tobacco and a desired degree of humidity which it possesses at the time of manufacture of the cigarette, the container will be wrapped in a wrapping 8 of some suitable paper such, for example, as paraffin paper, and as best shown in Figures 1 and 6 of the drawings.
- As heretofore stated, the invention contemplates the provision of means whereby the cigarettes, even though they be few in number, will be so presented, at the time of opening the container, that they may be readily removed therefrom without the necessity of feeling about within the container, and accordingly a rectangular sheet 9 of celluloid, or any other resilient or semi-resilient material possessing a suitable degree of stiffness, is arranged within the container prior to the packing of the cigarettes therein and against the rear wall of the container. By reference to Figure 5, it will be observed that when the container is opened, there will be a tendency to flex the sheet 9 substantially at its vertical middle, with the result that the free side portions thereof will, in tending to maintain the plane of the intermediate portion of the sheet, urge the cigarettes which are resting against them, toward the opening provided at the front of the container when the sections are relatively swung open, and thus the cigarettes are made readily available. Said sheet 9 may constitute a picture, a coupon, a premium card, or it may simply serve its purpose as a follower or partial ejector for the cigarettes.

- In the form of the invention shown in Figure 7 of the drawings, the rear or back wall of the container, which wall is indicated by the numeral 10, is integral throughout its width, so that this wall comprises a single piece of material as distinguished from the corresponding wall of the previously described form of the invention which is formed in sections having overlapped and united marginal portions. In this modified form a stiffening strip 11 is adhesively or otherwise secured to the inner face of the wall 10, and imparts to the vertical mid portion of said wall a sufficient degree of stiffness to adapt the container to be opened and closed in the same manner as the container embodying the first described prin-

ples of the invention. Likewise this stiffening strip constitutes a backing for the follower sheet 12 which corresponds to the sheet 9 previously described. Except in the respects noted, the form shown in Figure 7 ⁷⁰ does not differ materially from the form shown in the other figures of the drawings.

Having thus described the invention, what I claim is:

1. A container of the class described comprising a pair of sections each closed except at one side, the walls of the container being resiliently flexible, the open sides of the sections being diagonally disposed, and the sections at their said sides being interfitted with the marginal portions of their rear walls overlapped and united together. ⁷⁵

2. A container of the class described comprising a pair of sections each closed except at one side, the walls of the container being resiliently flexible, the open sides of the sections being diagonally disposed, and the marginal portions of the rear walls of the sections being overlapped and united together to form a vertical medial portion less ⁹⁰ flexible than the remainder of the rear wall.

3. A container of the class described comprising a pair of sections each closed except at one side, the walls of the container being resiliently flexible, the top and bottom walls of each section being of trapezoidal form whereby the rear wall of each section is of greater width than the front wall of said section, the open sides of the sections being interfitted with the marginal portions of their rear walls overlapped and united together to form a vertical medial portion less flexible than the remainder of the rear wall, and the said top and bottom walls at their free ends being mutually overlapped.

4. A container of the class described comprising a pair of sections each closed except at one side, the walls of the container being resiliently flexible, one section of the container being fitted at its open side into the other section of the container, the top and bottom walls of the sections being of trapezoidal form whereby to be mutually overlapped at their free ends, the marginal portions of the rear walls of the sections being overlapped and united together to form a vertical medial portion less flexible than the remainder of the wall.

5. A container of the class described comprising a pair of sections each closed except at one side, the sections being arranged with their open sides confronting each other and with their rear walls united substantially vertically medially of the back of the container, and a backing sheet arranged within the container against the inner side of the said back, and constituting means for projecting the contents of the container toward the front thereof when the container is spread open.

6. A container of the class described comprising a pair of sections closed except at one side, the walls of the container being resiliently flexible, the open sides of the sections being diagonally disposed, the sections at their said sides being interfitted with the marginal portions of their rear walls overlapped and united together, and resilient means disposed within the container tending to occupy a plane regardless of relative movement of the said sections away from each other about their united marginal rear wall portions.

7. A container of the class described comprising front, rear, side and top and bottom walls of resiliently flexible material, the said front wall being divided vertically medially

and the said top and bottom walls being divided along lines diverging from the front wall toward the rear wall whereby to provide overlapping portions at the top and bottom walls of the container, and a resilient sheet of material disposed within the container against the inner side of the back wall thereof and tending to occupy a plane regardless of relative movement of the divided halves of the container away from each other about the vertical medial portion of the back wall and constituting means for projecting the contents of the container toward the front thereof when the container is spread open.

In testimony whereof I affix my signature.

GEORGE H. GROSS. [L. s.]
